STAPLE PULLER

Thomas Evans, Jackson, Ohio

Application January 31, 1934, Serial No. 709,231

1 Claim. (Cl. 254—28)

This invention relates to a staple puller, the general object of the invention being to provide means for pulling staples from posts and the like without bending the staples and even when the staples are wholly embedded in the posts.

5 This invention also consists in certain other features of construction and in the combination and arrangement of the several parts, to be hereinafter fully described, illustrated in the accompanying drawing and specifically pointed out in the appended claims.

In describing the invention in detail, reference will be had to the accompanying drawing wherein like characters denote like or corresponding parts throughout the several views, and in

15 which:—

Figure 1 is a side view of the invention.

Figure 2 is an edge view thereof.

As shown in these views, the device comprises a pair of members A and B pivoted together by 20 the pin 1 and each comprising a handle part 2 which is preferably shaped and roughened, as shown, and the member A further includes a substantially hook-shaped part 3, while the member B includes an arcuate-shaped part 4 terminating in a reduced pointed part 5. This part 25 5 is of less width than the part 4, and this part 5 and the end of the part 4 forms a substantially straight wall 6, as shown in Figure 1. The part 3 extends outwardly from the pivot pin 1 substantially straight and then curves sharply inwardly to form the beak of the hook.

In using the tool, where the staple is not fully embedded in the post or other member, the beak of the part 3 is placed under the bight of the 35 staple and the jaws brought together and then the tool is rocked on the outer edge of the part 3 so as to pull the staple from the post, the closing of the two jaws preventing the staple from dropping from the device. However, if the staple 40 is fully embedded in the post, the point 5 is

forced into the post and under the bight of the staple and then the tool is moved toward the post so that the point 5 and a part of the wall 6 will force the staple out of the post. By closing the jaws when this is being done, the staple will be held by the device after it has been pulled 5 from the post.

As before stated, this tool will pull staples without bending them, so that they can be used again and staples can be easily and quickly removed from posts and other members, even when the staples are embedded in the post.

It is thought from the foregoing description that the advantages and novel features of the invention will be readily apparent.

It is to be understood that changes may be 15 made in the construction and in the combination and arrangement of the several parts, provided that such changes fall within the scope of the appended claim.

What is claimed is:—

20 A staple puller comprising a pair of members pivotally connected together and each comprising a handle part and a jaw part, one jaw part being bowed outwardly and terminating in a point of less width than the major part of the 25 jaw with its side edges curving from the base of the point to the pointed extremity thereof, the free end of said jaw having its inner face sloping outwardly from the concaved edge of the jaw to the convex edge thereof, said sloping face 30 extending from a point inwardly of the base of the point to the pointed extremity thereof, whereby said sloping face with the outer extremity of the convex edge makes the point of substantially wedge shape to enable said point to be 35 forced into a post under the bight part of a staple to enable the staple to be pulled from the post by a rocking movement of the device.
